FIG. III

UNITED STATES PATENT OFFICE

2,175,266

LOCOMOTIVE SMOKE BOX

Lloyd B. Jones, Altoona, Pa.

Application October 15, 1938, Serial No. 235,163

10 Claims. (Cl. 230—97)

This invention has general reference to equipment customarily located intermediate a source of combustion and an appropriate outlet to the open air for the discharge of smoke and, more particularly, to steam locomotive smoke boxes including reticulate means for retarding and arresting the escape of partly consumed fuel particles and sparks therefrom.

Means of the type referred to usually occupy a space between the forward edge of the table plate and the top and sides of the smoke box, and much difficulty has heretofore been experienced owing to the openings becoming plugged with unburnt sparks and so forth, with resultant increasing constriction of the free passage of the firebox gases to the stack. Such disadvantage necessarily involves frequent cleaning in order to insure efficient running of the locomotive.

The primary object of this invention is to overcome the stated objections by eliminating the reticulate spark arresting means from the direct path of the firebox gases, and at the same time directing the partly consumed fuel particles so that they are effectively broken-up or cooled off before passage to the locomotive stack, whereby the smoke box front end is rendered substantially self-cleaning or freed of unburnt fuel accumulation.

Another object is to arrange, in conjunction with the spark arresting means, a co-related diaphragm having a forwardly directed lip effective to compel the firebox gases and unburnt particles of the fuel to pass to the top of the firebox for downward deflection rearwardly of said diaphragm before entering the lift pipe for discharge, whereby the degree of spark reduction is further increased.

Further objects and ancillary advantages will be hereinafter referred to, or be apparent from the following description of a typical embodiment of this invention when considered in conjunction with the accompanying drawings, while the concluding claims tersely express the features of novelty on which patent protection is desired.

In the drawings:

Fig. I is a vertical section through the forward portion of a locomotive including the smoke box equipment of this invention.

Fig. II is a front elevation, drawn to a larger scale, of the same with the smoke box front and door removed, and parts broken out or in section for better illustration of otherwise hidden structural features.

Fig. III is a sectional plan, taken on the staggered plane III—III of Fig. I.

Fig. IV is a detail section on the line IV—IV in Fig. III; and,

Fig. V is a similar section on the line V—V of said Fig. III.

In all the views, corresponding parts are designated by like reference characters.

Referring more in detail to the drawings, the numeral 1 indicates the forward portion of a locomotive boiler shell, 2 the longitudinal flues, and 3 the head plate; while the smoke box is comprehensively designated 4, the same having a front plate 5 and door 6. Within the smoke box 4 is a standard exhaust-steam smoke-ejector 7 below the lift pipe 8 and stack 9; and 10 is the usual table plate about the ejector 7 with rearward connection to the vertical baffle plate 11, all of said parts being constructed and arranged in accordance with known practice.

In accordance with this invention at the forward edge of the table plate 10, in advance of the lift pipe 8, there is erected an imperforate sheet metal diaphragm 12, which extends transversely of the smoke box 4 and projects well above the lower end of the lift pipe 8, said diaphragm having a forwardly-projecting upwardly-inclined lip 13, which serves for a purpose later on explained. This diaphragm 12 is preferably made in counterpart sections, adapted to fit within the inner ring 20, with one of the medially meeting edges recessed at 14 for reception of the edge portion 15 of the other, and there connected by spaced wedge-pins 16. At the outer sides, the diaphragm 12 is rigidly supported by upper and lower angle-sections 17, 18, respectively and conveniently welded to the smoke box shell 19 and inner ring 20; and, along the lower edge said diaphragm is similarly secured by wedge pins 16 to the vertically turned edge 21 of the table plate 10.

In spaced relation to the diaphragm 12 there is mounted transversely of the smoke box front plate 5, what is usually termed, a "cinder buster" 22 preferably composed of perforate sheet material of a mesh so that some of the gases and also sparks, too small to do any material damage, may pass directly through the same. The cinder buster 22 shown conveniently comprises a main section 23, with aligned side sections 24; each such section embodying a rectangular frame 25 including a wire netting panel 26; and it is to be noted said buster 22 is inclined upwardly in the forward direction, see Figs. I, IV and V. Transversely of the smoke box 4 is mounted a

suitable bar 27, rigidly supported at the ends by angle-section brackets 28, preferably welded to the smoke box shell 19, said bar having the rear edges of the buster sections 23, 24 attached thereto by spaced wedge pins 30. The forward edge of the buster section 23 is similarly attached, by wedge pins 30 to a suitable-section composite bar 31, longitudinally shaped to fit transversely, or "chord-fashion", across the smoke box front 10 plate 5. This bar 31 includes stepped-sections 31' with which the ends of said bar lappingly engage and are connected together by wedge pins 30', while the ends of said stepped sections are rigidly fixed to the front plate 5 and front ring 29. 15 It is to be noted the forward component of the frame 25, of the main buster section 23, is preferably formed of angle cross-section to provide an abutment or lip *a* with which coacts an associated bar or imperforate baffle member 32, permanently secured across the smoke box door 6, 20 for preventing upward flow of any gases or sparks in front of the bar 31. Spaced angle-sections 33 are provided in connection with the buster side sections 24, and are rigidly fixed to the 25 front plate 5 to prevent upward displacement of said sections.

From the foregoing structural explanation of this invention, it will be apparent that by provision of the clearance *c* between the vertical 30 diaphragm 12 and the rear edge of the cinder buster 22, all netting 26 is eliminated from the direct path of the gases, while at the same time unburnt particles and large sparks are so directed, below the buster 22, that they are effectively broken-up or cooled-off before they can travel by way of the clearance *c* to the locomotive stack 9. It is also to be noted that by inclining the abutment or lip *a* slightly forward from the vertical, as shown, the particles and 35 sparks are directed into a turbulent zone, below the bar or baffle member 32, set up by the structural arrangement and co-relation of the parts thereat, which further serves materially in keeping the buster netting panels 26 free from clogging, such arrangement also rendering said panels self-cleaning in an obvious manner. Furthermore, unburnt particles and sparks entering the smoke box 4 from the flues 2 and below the table plate 10 travel with such velocity they cannot 40 turn upward through the clearance *c*, but are projected forward under their own velocity and strike the head plate 5 and door 6 underneath the cinder buster 22; the large particles or sparks of unburnt material impacting the 45 said parts 5, 6, and bouncing back against the under side of the buster 22, until they are sufficiently broken up to either pass through the buster netting panels 26 in minute particles, or 50 are sufficiently cooled off before they can be carried through the clearance *c*, and circuitous course defined by the diaphragm 12 to the stack 9. Incidentally, the diaphragm 12 with its lip 55 13 jointly have the effect of compelling the flow of gases and sparks to pass to the top of the smoke box 4 in a substantially vertical direction for further turbulent circulation before they can flow downward on the rear side of said diaphragm for passage into the lift pipe 8 and stack 60 9. The circuitous course thus set up causes comparatively little, or a negligible, retardation to the free passage of the gases, but substantially delays the discharge of "live" sparks out of the stack 9, even after they have passed the cinder 65 buster 22, so that they are effectively disinte-

grated or cooled off before exhaustion into the open air.

Finally, while a preferred embodiment of the invention has been illustrated and described, it will be appreciated modifications and changes 5 may be effected in adapting said invention to different application than the one specifically disclosed.

Having thus described the invention, I claim:

1. In a smoke box including a draft conduit, 10 a table plate and a lift pipe; an imperforate diaphragm across the smoke box in advance of and projecting from the table plate above the lift pipe lower end, and a perforate cinder buster spaced forwardly and upwardly with respect to the diaphragm, said cinder buster including a 15 blank portion with a downward lip jointly serving to project rearwards under turbulence any unburnt fuel particles for disintegration before circuitous passage upward and over the dia- 20 phragm into the lift pipe.

2. In a smoke box including a draft conduit, a table plate and a lift pipe; an imperforate diaphragm across the smoke box in advance of and projecting from the table plate well above 25 the lower end of the lift pipe, said diaphragm having a forwardly-directed and upwardly-directed lip along its upper edge, and a perforate cinder buster forwardly of the diaphragm, said cinder buster including a frontal blank section 30 with a rear inclined portion serving to project rearwards under turbulence any unburnt fuel particles for disintegration before circuitous passage upwards and over the diaphragm and then downwards into the lift pipe. 35

3. In a smoke box including a front plate and a draft conduit, a table plate and a lift pipe; an imperforate diaphragm across the smoke box in advance of and extending from the table plate front edge well above the lower end of the lift pipe, said diaphragm having a forwardly 40 and upwardly directed lip along its upper edge, and a perforate cinder buster spaced forwardly of the diaphragm, said cinder buster including a horizontal blank section with a downwardly inclined rear lip across the smoke box front plate 45 coactive with the cinder buster, to project downwardly under turbulence any unburnt fuel particles for disintegration before circuitous up-and-down passage over the imperforate dia- 50 phragm into the lift pipe.

4. In a steam locomotive smoke box including a front plate having a door, a smoke ejector, a table plate and a lift pipe; an imperforate diaphragm transversely across the smoke box and projecting upwards from the table plate well above the lower end of and in advance of the lift pipe, and a perforate cinder buster spaced forwardly of the diaphragm, said cinder buster including a baffle section across the smoke box 60 front plate and door, said section having a rear downwardly-directed lip, and both jointly serving to project inwards under turbulence unburnt cinders or sparks for effective disintegration and cooling-off before passage up-and-down 65 over the imperforate diaphragm for escape by way of the locomotive smoke stack.

5. In a steam locomotive smoke box including a front plate having a door, a smoke ejector, a table plate and a lift pipe; an imperforate dia- 70 phragm transversely across the smoke box and projecting upwards from the table plate front edge vertically in advance of the lift pipe as well as extending well above the lower end of said lift pipe, and a perforate cinder buster spaced 75

forwardly of the diaphragm, said cinder buster including a blank baffle section across the smoke box front plate and door and jointly directing inwards under turbulence all unburnt cinders or sparks for effective disintegration and cooling-off before passage forwardly-up and rearwardly-down over the imperforate diaphragm and exit by way of the locomotive smoke stack.

6. In a steam locomotive smoke box including a smoke ejector, a table plate and a lift pipe; an imperforate diaphragm transversely across the smoke box projecting vertically upwards from the table plate and spacedly in advance of the lift pipe as well as extending well above the lower end of said lift pipe, said diaphragm at the sides fitting in the smoke box inner ring and having an upwardly-and-forwardly directed deflector lip along its upper edge, and an inclined perforate cinder buster spaced in advance of the diaphragm across the smoke box front end, said cinder buster including an imperforate horizontal blank portion with a downward lip inclined forwards from the vertical and serving in conjunction with the smoke box front plate to project downwardly inwards under turbulence all unburnt cinders or sparks for effective disintegration and cooling-off before passage over the imperforate diaphragm for exit from the locomotive smoke stack.

7. In a steam locomotive smoke box including a smoke ejector, a table plate and a lift pipe, an imperforate diaphragm projecting upwards from the table plate in advance of the lift pipe and extending well above the lower end of the lift pipe, said diaphragm at the sides fitting in the smoke box inner ring and having a deflector lip along its upper edge, and a perforate cinder buster spaced forwardly of the diaphragm, said cinder buster including a blank section effective to project rearwards and downwardly under

turbulence any unburnt fuel particles for disintegration of such unburnt fuel particles and the effective cooling-off of sparks contained in the smoke before discharge into the open air.

8. The combination of claim 7 wherein the imperforate diaphragm comprises counterpart sections with one of the meeting edges recessed for reception of the other, said diaphragm being removably attached to the table plate front edge and at the sides to angle sections secured to the inner face of the smoke box wall, and the deflector lip of the diaphragm is forwardly and angularly directed upwards with respect to the horizontal.

9. The combination of claim 7 wherein the perforate cinder buster comprises an intermediate and outer sections, the intermediate section extending across the smoke box front plate door opening and the outer sections laterally therefrom to the smoke box front ring and wall, each said section consisting of a frame with a netting panel, and a transverse bar across the smoke box for rearwardly and removably supporting the cinder buster, with similar supporting means across the front plate.

10. The combination of claim 7 wherein the cinder buster comprises an intermediate and outer sections, each outer section being removably attached along its inner edge to a transverse bar across the smoke box and stepped bars secured to the front plate, the intermediate section being similarly attached at its inner part to said transverse bar and at the outer part having an angle-section bar with its ends lappingly attached to the adjoining stepped bar ends, and a baffle member across the smoke box door adapted to abut to the intermediate section bar when said door is closed for preventing upward passage of unburnt cinders or sparks.

LLOYD B. JONES. 40
